UNITED STATES PATENT OFFICE

WILLIAM A. WULLE, OF CHICAGO, ILLINOIS, ASSIGNOR TO THE PYLE-NATIONAL COMPANY, OF CHICAGO, ILLINOIS, A CORPORATION OF NEW JERSEY

LAMP SOCKET AND GRIP

Application filed April 9, 1928. Serial No. 268,469.

My invention relates to improvements in electric light sockets and has for one object to provide a new and improved form of socket which will hold an inflated electric lamp base in place without danger of vibrating or jar- 5 ring loose. Other objects will appear from time to time throughout the specification and claims.

My invention is illustrated more or less 10 diagrammatically in the accompanying drawings, wherein—

Figure 1 is a side elevation;

Figure 2 is an elevation viewed from right angles to Figure 1;

15 Figure 3 is a section along the line 3—3 of Figure 5;

Figure 4 is a section along the line 4—4 of Figure 5;

Figure 5 is a plan view;

20 Figure 6 is a perspective view of the bottom section;

Figure 7 is a perspective of the holding spring.

Like parts are indicated by like characters 25 throughout the specification and drawings.

A is a base; A¹ a socket piece attached to the base. The base A is recessed as at A². The socket piece is apertured clear through and held in place on the base by the screws 30 A³, which passes through the socket and the base. Contained within the insulating socket A¹ is the threaded conductor socket A⁴, the screws A² passing through it and being threaded into the base.

35 On the bottom of the socket piece is a spring contact button B connected to the terminal B¹. The threaded conductor socket A⁴ is of course out of electric contact with the members B B¹. This socket A⁴ is threaded to 40 engage the usual type of threaded lamp base. It differs from the ordinary type of threaded socket in that it has diametrically opposed slots B² B² in which are spring fingers B³ B³, which fingers are recurved as indicated and 45 are in electric contact with the socket and project inwardly beyond the threads so as to come into yielding engagement with the threaded base of the lamp. B⁴ is an anchored ring through which the screws A³ pass and 50 from which project upwardly the springs B³

whereby the parts are held in working relation.

When a lamp is screwed into the socket the base as it penetrates pushes the spring fingers aside so that the base can be screwed 55 home in the usual manner with the spring fingers gripping the base on opposite sides. The yielding flexible gripping of these two fingers holds the lamp against vibration and movement and prevents it from 60 vibrating or rattling loose. The fact that the two spring fingers are integral with the anchored ring insures that the holding of 65 the lamp will be done by the springs only without any added load on any other part of the lamp and makes it possible to substitute this device for the standard device by merely introducing a slotted, threaded socket and the spring fingers.

I claim:

1. A socket for screw base electric lamps and the like, comprising an insulating base, an insulating socket-piece mounted thereon, a conducting socket contained within the insulating socket-piece and interiorly threaded 75 to engage a lamp base, a contact member arranged adjacent the bottom of the insulating socket, the inner periphery of the threaded conducting socket being longitudinally slotted, a conductor ring surrounding the 80 contact member in the bottom of the socket and out of electric contact with it, a spring finger projecting upwardly from such ring lying within the slot and having a recurve end adapted to engage the bottom of the 85 slot, the central portion of the spring finger projecting inwardly inside the threaded portion of the socket.

2. A socket for screw base electric lamps and the like, comprising an insulating base, 90 an insulating socket-piece mounted thereon, a conducting socket contained within the insulating socket-piece and interiorly threaded to engage a lamp base, a contact member arranged adjacent the bottom of the insulating 95 socket, the inner periphery of the threaded conducting socket being longitudinally slotted, a conductor ring surrounding the contact member in the bottom of the socket and out of electric contact with it, a spring 100

finger projecting upwardly from such ring lying within the slot and having a recurve end adapted to engage the bottom of the slot, the central portion of the spring finger projecting inwardly inside the threaded portion of the socket, there being a plurality of said slots and a spring finger projecting upwardly from the ring and lying in each such slot.

Signed at Chicago, county of Cook and
10 State of Illinois, this fifth day of April, 1928.

WILLIAM A. WULLE.
